UNITED STATES PATENT OFFICE

162,331

SLINGSHOT

Melvin G. Miller, Houston, and Talley W. Nichols,
Pasadena, Tex.; said Miller assignor to said
Nichols

Application October 25, 1948, Serial No. 149,284

Term of patent 14 years

(Cl. D34—15)

To all whom it may concern:

Be it known that we, Melvin G. Miller and Talley W. Nichols, citizens of the United States, residing at Houston and Pasadena, respectively, in the county of Harris in the State of Texas, have invented a new, original, and ornamental Design for a Sling Shot, of which the following is a specification, reference being had to the accompanying drawings, forming a part hereof.

Figure 1 is a side view of a sling shot showing my new design.

Figure 2 is an end view with the elastic bands partly broken away.

Figure 3 is a front, elevational view, and

Figure 4 is a rear elevational view with the elastic bands shown in section.

Figure 5 is a perspective view of the sling shot.

We claim:

The ornamental design for a sling shot, as shown.

MELVIN G. MILLER.
TALLEY W. NICHOLS.
